The ornamental design for a chair, as shown and described.

DESCRIPTION

FIG. 1 is a front perspective view of a chair illustrating my new design;

FIG. 2 is a front elevational view;

FIG. 3 is a rear elevational view;

FIG. 4 is a left side view;

FIG. 5 is a right side view;

FIG. 6 is a top plan view; and,

FIG. 7 is a bottom plan view.

The broken lines in the drawings illustrate portions of the article that form no part of the claimed design. The shade lines, if any, represent surface shading and not surface ornamentation, color, or material type.
